UNITED STATES PATENT OFFICE.

HARRY S. DAVIS, OF INDIANAPOLIS, INDIANA.

WINDOW-FRAME.

1,316,224.

Specification of Letters Patent. Patented Sept. 16, 1919.

Application filed February 14, 1919. Serial No. 277,007.

To all whom it may concern:

Be it known that I, HARRY S. DAVIS, a citizen of the United States, residing at Indianapolis, Marion county, and State of Indiana, have invented and discovered certain new and useful Improvements in Window-Frames, of which the following is a specification.

My invention consists of an improved construction of weather strips for window sash, whereby the joint between the sliding sash and the window frame is completely closed against the passage of any air or dirt, and also whereby the use of a strip separating the ways in which the upper and lower sash slide, and also molding at the sides of the sash, are avoided, all as will be hereinafter more fully described and claimed.

Referring to the accompanying drawing, which is made a part hereof, and on which similar reference characters indicate similar parts,

Figure 1 is a cross section through one side of a window frame and sash, mounted with my improved weather strip, and illustrating its construction, and

Figs. 2 and 3 detail views showing the form of the parts more clearly.

In said drawing the portions marked A represent the part of the window frame against which the sash usually run in operation; B the lower sash and C the upper sash of the window.

All of the above mentioned parts are or may be of any approved or appropriate construction and require no special description herein.

My improved weather strip 10 consists of a metal plate adapted to extend from the top to the bottom of the part A of the frame, covering the outside half of the face thereof, and is formed with two vertical beads 11 and 12 united by a web 13, which beads also extend substantially from the top to the bottom of the frame. On the adjacent corners of the respective sash B and C are mounted metal strips or plates 14 and 15 formed with grooves which correspond in form, in cross-section, to the shape of the beads 11 and 12 and are adapted to fit over said beads and run thereon. Said parts 14 and 15 are set into the adjacent corners of the respective sash, as shown. The web 13 is of a length to space the beads 11 and 12 apart that distance required to permit the free movement of the sash by each other in operation up

and down. In other words it spaces the sash apart in the same manner as the usual strip which is secured to the frame between such sash. These interlocking beads and grooves 60 formed of metal, one secured to the frame and the other to the sash, form a rigid support for the sash in a vertical direction and also completely close the joint between the sash and frame, thus serving perfectly the 65 purposes of a weather strip and in addition avoid the necessity and expense of the moldings usually used on both the outside and the inside of the frame against the sash as well as the strip usually employed between 70 the sash.

The plate 10 covers the outside face of the jamb and thus protects it from the weather, prolonging the durability of the structure. In the drawing these parts are shown as 75 somewhat separated from each other, the distance of separation being exaggerated in order to illustrate the construction more clearly. It will be understood that the parts are so fitted that they run freely, but with 80 no unnecessary space between them. Another advantage obtained by the invention is that it dispenses with the necessity of a molding, or holding strip, on the inside of the window frame, leaving the closure to the 85 pocket for access to the sash weights accessible by merely raising the lower window sash to above said pocket. These and various other advantages, as material saving of expense, will readily suggest themselves to the 90 user.

Having thus fully described my said invention, what I claim as new and desire to secure by Letters Patent is:

1. A weather strip comprising a sheet of 95 resilient metal provided with a portion having oppositely directed spaced beads, a second portion integral therewith adapted to be permanently attached to a window frame and tending to hold the beads spaced yieldingly away from the frame position, and other independent strips provided each with a marginal curvature complementary and proportioned to slidably embrace one of the beads and to be attached respectively to an 105 upper and a lower sash.

2. A weather strip comprising a sheet of resilient metal provided with a portion having spaced beads, a second portion integral therewith adapted to be permanently attached to a window frame and tending to hold the beads spaced yieldingly away from 110

the frame position and other strips provided each with a marginal curvature complementary and proportioned to slidably embrace one of the beads and to be attached 5 respectively to an upper and a lower sash with their open sides adjacent to each other.

In witness whereof, I have hereunto set

my hand and seal at Indianapolis, Indiana, this 27th day of January, A. D. nineteen hundred and nineteen.

HARRY S. DAVIS. [L. S.]
